UNITED STATES PATENT OFFICE.

WALTER E. MURPHY, OF NEW YORK, N. Y.

DUMP CAR.

1,406,274.

Specification of Letters Patent. Patented Feb. 14, 1922.

Application filed January 25, 1919. Serial No. 273,116.

To all whom it may concern:

Be it known that I, WALTER P. MURPHY, a citizen of the United States, residing at New York city, in the county of New York and State of New York, have invented certain new and useful Improvements in Dump Cars, of which the following is a specification.

My invention relates to railway dump cars, and particularly to the construction of the doors or hinged bottom panels in cars of this type; and the primary object of the invention is to provide a door or bottom panel which will be very strong and rigid so that it will not sag under the load or become bent or warped under the stresses to which it is subjected and which, moreover, will present a smooth and unobstructed surface in contact with the cargo over which the cargo will readily slide when it is dumped. Considerable difficulty has been experienced in cars of this type due to the sagging, warping and bending of the bottom doors, which as will be readily understood, are subjected to very heavy pressures from the bulk material with which these cars are loaded, and are liable to other strains when manipulated due to clogging of the parts with ice or other substances. Any warping of the hinged bottom doors or panels is likely to interfere with the proper manipulation of the dumping mechanism of the car besides making the car leaky. It has been customary to reinforce these doors with angle bars riveted to the under side thereof but this expedient has not proved altogether satisfactory, so far as giving the requisite strength and rigidity. Moreover, any such reinforcement adds to the weight of the doors besides making the upper surfaces of the doors rough. In order that the cargo of pulverulent material, such as sand or coal in that state, should be readily discharged, the upper surfaces of the doors ought to be as smooth as possible so that the load will readily slide over the same when the doors are let down. If the doors are studded with rivets a cargo of this sort will often clog particularly if moist. My invention provides a bottom door for a dump car which avoids these objections and at the same time is strong and sufficiently rigid to meet all requirements. The door, however, has a certain elasticity or flexibility which gives the structure capacity to spring back to its original shape when subjected

to such forces that some deflection is unavoidable. The invention, therefore, consists in the novel and improved constructions and arrangements, to be hereinafter described and claimed, for carrying out the object above stated and such other incidental objects as will be hereinafter described.

The invention is applicable to dump cars of different design and construction. I have shown in the drawings annexed hereto, and will describe in the following specification two well known types of railroad dump cars furnished with the hinged dumping doors constructed in accordance with the principles of my invention, with the understanding, however, that these embodiments of the invention are merely illustrative.

In the drawings,

Fig. 1 is a fragmentary plan view of one of the illustrative embodiments of my invention just referred to.

Fig. 2 is a sectional view on line 2—2 of Fig. 1.

Fig. 3 is a plan view of the sheet metal panel forming one of the doors of the car shown in the preceding two figures.

Fig. 4 is a sectional view on line 4—4 of Fig. 3.

Fig. 5 is a fragmentary sectional view on line 5—5 of Fig. 4.

Fig. 6 is a fragmentary longitudinal sectional view of the other illustrative embodiment of the invention.

Fig. 7 is a fragmentary plan view of the same.

Fig. 8 is a vertical sectional view on line 8—8 of Fig. 7.

Fig. 9 is a plan view, on an enlarged scale, of one pair of doors.

Fig. 10 is a sectional view on line 10—10 of Fig. 8, and

Fig. 11 is a view, in perspective, of one corner of the door panel.

Like characters of reference designate like parts in the several figures of the drawings.

Referring first to Figs. 1 to 5 inclusive, 25 indicates the center sill of the car, 26 one of the bolsters, 27, 27 the side walls, 28, 28 the end walls, 29 the outside side wall stakes, 105 and 30 the interior stakes which engage the bolster.

It will not be necessary to describe in detail the general structure of the car as my invention is confined to the construction and arrangement of the bottom doors.

Each door consists of a sheet of metal 31

which, in the type of car under consideration, is hinged to the center sills 25 by hinges 32. Chains 33 engage brackets 34 on the outer edges of the doors. These chains form part of the dumping mechanism which is manipulated to drop or raise the doors.

The panel 31 is formed with a plurality of substantially parallel corrugations 35 which are preferably upwardly pressed from the sheet and which terminate within the edges of the sheet so as to leave flat margins 36. The corrugations extend transversely of the car, that is to say, in the direction in which the cargo moves when it is dumped. These corrugations merge one into the other so that the panel has a sinuous configuration in cross section. This configuration gives the panel very considerable strength. The corrugations act as beams to transmit the stresses exerted against it by the cargo from one edge of the panel to the other. Each corrugation rigidifies the other due to the merging of one into the other so that if the pressure on one corrugation is greater than on another there will be a disposition of stresses from one corrugation to another which aids in preventing undue deflection. Moreover, the sinuous configuration of the panel gives it a certain increased elasticity whereby it will tend to resume its original shape if the force is such that some deflection is unavoidable. The edges of the panel are provided with a rigidifying element consisting preferably of an integral downturned flange 37 which preferably extends continuously around all four edges of the sheet. The portions of this flange along the edges parallel with the corrugations are preferably given a truss-shape, as indicated at 38. These are the unsupported edges of the door and consequently require more reinforcement than the other edges which are engaged by the hinges or chains. The truss-like flanges cooperate with the corrugations to give a panel the required strength and stiffness on lines transverse of the car. It is along these lines that deflection under the load is likely to occur.

A modified construction to suit a somewhat different type of car is shown in Figs. 6 to 11, inclusive. In this type of car the doors are hinged on lines running crosswise of the car instead of lengthwise thereof and operate in sets of four. The side walls of the car are shown at 39 and the fixed sloping bottom sheet at one end of the car is indicated by numeral 40. A structure 41 extends the length of the car presenting in plan two somewhat sloping surfaces 42, 42, this structure forming, in effect, a part of the center sill of the car. Transversely of the car at intervals are fixed structures 43 having approximately an inverted V-shape in cross section. They extend, in each case, from the side walls of the car to the longitudinal

structure 42. The hoppers formed by the side walls of the car, the longitudinal structure 41, the fixed bottom sheet 40 and the transverse structure 43 are closed at the bottom, in each case, by a pair of doors 44, 45, the former being hinged at 46 to one of the transverse structures 43 and the latter being hinged at 47 to the fixed bottom sheet 40. Each of these doors consists of a sheet metal panel formed with corrugations 46 extending transversely thereof, that is, longitudinally with respect to the car. These panels are formed, except on their meeting edges, with downturned flanges 48, 49, these flanges being rigidly united by corner angles 50. Secured to the under side of the meeting edges of the panels are angle bars 51 which extend under the longitudinal structure 41 and are connected with the corresponding edges of the aligning doors on the other side of the car. The flanges 48 are preferably secured to the angle bars 51 by members 52. The mechanism for operating the doors is engaged with the angle bars 51, the chains forming part of this mechanism being indicated in dotted lines at 53 (Fig. 6). This mechanism forms no part of my invention and need not be described.

I claim:

1. In a railway dump car, the combination with the body of the car, of a hinged door forming part of the bottom of the car and adapted to assume an inclined position for dumping, comprising a sheet steel panel formed with rigidifying means at its edges and with corrugations which are pressed upwardly from the plane of the panel and extend in the direction of movement of the cargo when dumped.

2. In a railway dump car, the combination with the body of the car, of a hinged door forming part of the bottom of the car and adapted to assume an inclined position for dumping, comprising a sheet steel panel formed with rigidifying means at its edges and with a plurality of parallel corrugations which are pressed upwardly from the plane of the panel and terminate within the edges of said sheet and extend in the direction of movement of the cargo when dumped.

3. In a railway dump car, the combination with the body of the car, of a hinged door forming part of the bottom of the car and adapted to assume an inclined position for dumping, comprising a sheet steel panel formed with rigidifying means at its edges and with corrugations which terminate within the edges of the sheet, project upwardly from the plane of the margins of the sheet, and extend in the direction of movement of the cargo when dumped.

4. In a railway dump car, the combination with the body of the car, of a hinged door forming part of the bottom of the car and adapted to assume an inclined position for

dumping, comprising a sheet steel panel formed with downturned rigidifying flanges at its edges and with corrugations forming parallel furrows above the plane of the sheet which extend in the direction of movement of the cargo when dumped.

5. In a railway dump car, the combination with the body of the car, of a hinged door forming part of the bottom of the car and 10 adapted to assume an inclined position for dumping, comprising a sheet steel panel formed with rigidifying flanges at its edges which are united to form a continuous rigidifying element around the panel and with a 15 plurality of up pressed, parallel corrugations which extend in the direction of movement of the cargo when dumped.

6. In a railway dump car, the combination with the body of the car, of a hinged door 20 forming part of the bottom of the car and adapted to assume an inclined position for dumping, comprising a sheet steel panel formed with an integral, continuous, downturned rigidifying flange around its edges 25 and with up pressed corrugations which provide parallel furrows above the plane of the sheet and extend in the direction of movement of the cargo when dumped.

7. In a railway dump car, the combination 30 with the body of the car, of a hinged door forming part of the bottom of the car and adapted to assume an inclined position for dumping, comprising a sheet steel panel formed with an integral, continuous, downturned rigidifying flange around its edges 35 and with parallel corrugations which extend in the direction of movement of the cargo when dumped, terminate within the edges of the sheet and project upwardly from the 40 plane of the margins of the panel.

8. In a railway dump car, the combination with the body of the car, of a hinged door forming part of the bottom of the car and 45 adapted to assume an inclined position for dumping, comprising a sheet steel panel formed with downturned rigidifying flanges at its edges and with a plurality of corrugations which terminate within the edges of the sheet, project upwardly from the plane of 50 the margins of the panel and extend in the

direction of the movement of the cargo when dumped.

9. In a railway dump car, the combination with the body of the car, of a hinged door forming part of the bottom of the car 55 and adapted to assume an inclined position for dumping, comprising a sheet steel panel formed with corrugations which extend in the direction of movement of the cargo when dumped and with downturned flanges, wider 60 at the middle than at the ends, along the edges parallel to said corrugations.

10. In combination with the body of a railway dump car, of a door, means for hinging the door to the bottom of the car body, 65 means for supporting the edge of the door opposite the hinges when the door is closed; the door comprising a sheet metal panel formed with corrugations which extend substantially from the hinged edge of the door 70 to said opposite edge, and provided with means constituting a unitary rigidifying element extending around the edges of the door to the bottom thereof.

11. A hinged door for a railway dump car 75 comprising a sheet metal panel provided on the outside with rigidifying means extending around its edges and formed with corrugations which project inwardly of the car, providing furrows above the plane of said panel 80 and lie in the direction of movement of the cargo when dumped.

12. A hinged door for a railway dump car comprising a sheet metal panel formed with outturned rigidifying flanges at its edges and 85 with corrugations which terminate within the edges of the panel, project inwardly of the car so as to provide furrows above the plane of said panel and lie in the direction of movement of the cargo when dumped. 90

13. A hinged door for a railway dump car, comprising a sheet metal panel formed with outturned rigidifying flanges united at the corners of the panel to provide a continuous, rigidifying element around the same, 95 said panel being formed with corrugations which terminate within the sheet and merge one into the other so that the panel has a sinuous configuration in cross section.

WALTER P. MURPHY.
